UNITED STATES PATENT OFFICE.

FRED W. A. TECHMER, OF LA CROSSE, WISCONSIN, ASSIGNOR TO B. F. AVERY AND SONS, OF LOUISVILLE, KENTUCKY, A CORPORATION OF KENTUCKY.

PLOW.

Application filed October 1, 1915. Serial No. 53,533.

To all whom it may concern:

Be it known that I, FRED W. A. TECHMER, a resident of La Crosse, in the county of La Crosse and State of Wisconsin, have invented 5 certain new and useful Improvements in Plows, of which the following is a full, clear, and exact description.

The invention relates to plows and has for its purpose to provide simple and efficient 10 means whereby the plow share may be firmly secured to the frog and moldboard of the plow, or readily and quickly detached therefrom.

The invention consists in the several novel 15 features hereinafter set forth and more particularly defined by claims at the conclusion hereof.

Figure 1— is an inverted plan of the plow showing the parts connected together. Figure 2— is an underneath perspective view of the plow with the plow tilted considerably on the cutting edge of the share. Figure 3— is an underneath perspective view of the plow, the plow being tilted somewhat 25 upon its point and showing an angular relation of a lug and threaded rod. Figure 4— is a rear view of the plow tilted upon the wing corner of the cutting edge of the share and showing a different angular relation 30 of the lug and the rod. Figure 5— is a detail on the line —a—a— of Figure 2. Figure 6— is a view of the clamping lug showing the vertical face adjacent to the landside share and the vertical portion of 35 the frog. Figure 7— is a top view of the clamping lug. Figure 8— is a side view of the locking lever and support for the connecting rod between the lug and the lever. Figure 9— is a view of the face of the lever 40 adjacent to the moldboard and share.

The plow consists of a beam 1, rear landside plate 2, and moldboard 6, all being firmly attached to the frog 5. The share 4 consists of the vertical landside portion 3 and the wing portion 4^a which is secured 45 to the frog and the moldboard by means hereinafter described. The frog conforms to and fits against the back face of the moldboard and is secured thereto in the usual 50 manner. The frog 5 is made with angular portions, one portion being vertical and curving rearwardly and upwardly and to which the rear landside plate 2 is attached,

and a wing portion 5^x curved to follow the curvature of the share and moldboard, thus 55 affording a support for the moldboard and landside on its upper face and to both portions of which the beam is secured by ordinary means not shown herein.

In Fig. 5 the end of the landside of the 60 frog is indicated by 5^a, its free corner by 5^d, the end of the wing of the frog by 5^e and its free corner by 5^b.

Attached to the landside 3 of the share is a lug 7, which may be fastened to the landside in a suitable manner through the hole 7^c and having an offset portion 7^r, the offset portion being thinner than the thickness of the frog 5 as is shown in Figures 1, 2, 3 and 4, the arm of the lug extending inwardly from its angle with the offset so as to pass the corner 5^d of the vertical portion of the frog angularly, so that while the share is being seated on the frog and against the lower edge of the moldboard the face 7^a of the lug will have a wedging action 75 against the vertical corner 5^d of the frog and aid in bringing the share into proper seating position on the plow.

The upper face of the lug has the downward offset 7^e, see Figures 2, 3, and 6, the offset being shorter than the thickness of the frog as is shown in Figures 2 and 3, and from the lower end of the offset the upper face of the lug extends upwardly and rearwardly with the face 7^g lying beneath and adjacent to the lower corner 5^b of the forward end of the wing portion of the frog as is shown in Figures 2, 3 and 5, and being at an angle with the under surface of the frog. In Figure 5 the line 5^e is intended 80 to show the contour of the under face of the frog, and from which the angle of the face of the lug 7^g with the frog is clearly shown.

From this relation of the face 7^g to the forward end of the wing portion of the frog it is manifest that as the share is drawn to position, the face 7^g will contact the corner of the frog 5^b with a wedging effect, resulting in seating the wing of the share firmly upon the upper face of the frog when the rear edge of the share is seated against the lower edge of the moldboard and against the forward edge of the landside plate 2.

By this means there is provided a double

wedging surface on the lug for drawing the landside of the share against the outer vertical wall of the frog wingwardly, and the wing of the share downwardly upon the face 5 of the frog, as the share is being pulled rearwardly to its final position adjacent to the moldboard.

In Figure 5 the landside 3 and wing 4^a are shown in cross section, the forward end 10 of the lug also is shown in cross section on the line a—a Fig. 2 and the wedging effect in both directions is clearly manifest.

From the examination of Figures 1, 2, 3, 4 and 5, it is manifest that the inner face of 15 the landside, the under face of the share, the landside face 7^a of the lug and the upper face 7^c of the lug form a socket into which the nose or forward end of the frog protrudes as the share is drawn to place, the 20 socket being open on its under and wing sides, and when the share is finally seated, preventing lateral and vertical movement of the share with relation to the frog.

Rearwardly of the angular faces 7^a and 7^c 25 the lug is bent at a sharper angle to the vertical wall of the frog, seen more clearly in Figures 1 and 5.

Fastened to the wing portion of the moldboard is a lever pivoted at 10 near the lower wing portion of the moldboard, by means of the pin 10^a extending through the bolt hole 10^b and properly secured to the moldboard, and extending rearwardly and upwardly; and at its upper end having a fork 9^b with the jaws 9^c forming the open slot 9^a, see Figures 8 and 10. At the rear face of the jaws is a round counter sunk portion 9^d, see Figures 8 and 9, to receive a washer 9^e, shown in dotted lines in Figure 8. The 40 rear wall of the slot 9^a is shown sloped to allow of a considerable angle of the rod with the support 9, see Figure 1. Between the jaws and through the washer passes the rear end of the threaded rod 8 having the adjusting nut 8^b in the rear of the fork and contacting the washer. The forward end of the rod is pivotally attached to the rear of the lug through the hole 7^d therein, the pivotal relation being a loose one, affording 45 a universal movement. Figure 1 shows the rod and the lever in position when the share has been properly seated over the frog and against the moldboard.

Extending downwardly beneath the rear portion of the share is the hook portion 11 of the lever, formed with a bevelled face 13, and adapted to wedgingly engage the rigid button 12 on the under or rear face of the wing portion of the share. The rear wall 60 of the hook 11 forms a stop for the lever or support 9. To release the share from the plow all that is necessary is to loosen the nut sufficiently to lift the washer from the recess, when the rod can be slipped out of the slot 9^a. The lever is then given a rear-

ward push to free it from the button 12, when the share can be readily removed from its position.

To again secure the share the upper end of the lever is swung forwardly, the rear end 70 of the rod swung into the slot 9^a, the washer inserted in the counter sink 9^d and the nut screwed down to the rod, when there will be a conjoint action of the lever, the rod and the lug to seat the share again firmly in 75 position. Frequently the shares are warped somewhat and the bevelled edge 13 is used to bring the rear of the share down to a level with the moldboard.

The operation of attaching and detaching 80 the share is very simple and very quickly performed.

By examining Figures 1 and 4, it will be seen that the rod and lug are at an angle 85 wingwardly with the landside and vertical portion of the frog and also that from the vertical corner 5^d of the frog to the point of support of the rear of the rod 8 in the fork 9^b as a straight line indicated by the diagrammatical dotted line A; the lug and rod are transversely at an angle to each other.

By examining Figs. 2 and 3, which give something of a side view of the plow from the moldboard side, it will be found that 95 from the corner 5^b of the forward wing portion of the frog to the point of support of rod 8 in the support 9, as a straight line indicated by the dotted diagrammatical line B the lug and the rod are at an angle to each other in a vertical direction.

It is manifest that as the nut 8^b is tightened against the fork 9^b and because of the two angular relations of the lug and rod above described, the rear of the lug will 105 be forced sideways toward the vertical wall of the frog against the corner 5^a and upwardly toward the under face of the frog and against the corner 5^b thereof, with a clamping effect.

From the construction, relation and manipulation of this lug in seating the share, it will be seen that three results are produced; viz, a right angle socket is formed 115 between the share and lug for the reception of the nose or forward end of the frog; a wedging effect, and also a clamping effect are secured, all of which aid in very quickly and firmly seating the share, and permitting of its almost instant release. The ordinary seating of a share on a plow involves a bolt hole in the wing near the landside and toward the rear wall of the share, a bolt passing through the share and the frog and secured by a nut on the under side of 125 the frog. But this construction involves a weakness in the share demonstrated repeatedly when striking obstructions in the breaking of the share from its forward edge and backwardly across the bolt hole. By 130

the use of the lug involved in this invention, if made properly, this bolt hole is entirely dispensed with, the contact of the lug with the frog in the two directions described being amply sufficient to hold the share to its place even in very severe conditions of plowing.

In very narrow plows the lug alone would be sufficient to hold the share in place; but in plows of wider cut the addition of the hook 11 is desirable. In very large plows it may be desirable to form a slot centrally placed and in the forward edge of the frog to receive the button on the share as sometimes in tempering a share the center of its rear edge bows unduly upwardly and needs to be drawn down to proper alignment with the edge of the moldboard, which the button in the centrally placed slot will do.

20 The invention is not to be restricted to the details set forth, since these may be modified within the scope of the appended claims without departing from the spirit and scope of the invention.

25 Having thus described my invention, what I claim as new and desire to secure by Letters Patent is:

1. In a plow, the combination of a moldboard, a detachable share having a vertical 30 landside and a wing portion, and a frog beneath the moldboard and wing of the share, having a vertical and a wing portion, with a lug on the inner face of the share landside adapted to come into clamping relations with the vertical and wing portions of the frog to lock the share, and means on the plow for drawing the lug into clamping position.

2. In a plow, the combination of a mold- 40 board, a detachable share having a landside and a wing portion, and a frog beneath the moldboard and wing portion of the share and having a vertical and a wing portion, with means for clamping the share in position comprising a lug on the inner face 45 of the landside of the share projecting inwardly and upwardly in clamping relations with the vertical and wing portions of the frog.

50 3. In a plow, the combination of a moldboard, a detachable share having a landside and a wing portion, and a frog beneath the moldboard and the wing portion of the share and having a vertical and a wing portion, with a lug on the inner face of the share landside projecting inwardly and upwardly to come into clamping relations with the end of the frog, and means for drawing the lug into clamping position.

60 4. In a plow the combination of a moldboard, a detachable share having a landside and a wing portion, and a frog beneath the moldboard and wing portion of the share, having vertical and wing portions, 65 with a lug attached to the inner face of the

landside of the share and projecting inwardly with a vertical wall adapted to come into clamping relations with the forward end of the vertical portion of the frog, and means for drawing the lug into clamping 70 position.

5. In a plow, the combination of a moldboard, a detachable share having a landside and wing portion, and a frog beneath the moldboard and the wing portion of the share, with a lug on the inner face of the landside of the share and projecting angularly inwardly and upwardly therefrom and having a horizontal face adapted to come into clamping relations with the forward 80 end of the wing portion of the frog, and means for drawing the lug into clamping position.

6. In a plow, the combination of a moldboard, a share having a landside and a wing portion, and a frog beneath the moldboard and the wing portion of the share having vertical and wing portions, with a lug on the inner wall of the landside of the share projecting inwardly and rearwardly and 85 adapted to clamping relations with the frog, a support on the plow spaced horizontally away from the vertical wall of the frog, and an adjustable connection between the support and the lug, said connection and the 90 lug being angularly arranged with respect to each other in a transverse direction and to the longitudinal direction of the landside of the share.

7. In a plow, the combination of a moldboard, a detachable share having a landside and a wing portion, and a frog beneath the moldboard and wing portion of the share and having a vertical and a wing portion, with a lug on the inner face of the landside 105 of the share and adapted to clamp against the free corners of the forward end of the frog, and means for holding the lug in clamped position.

8. In a plow the combination of a moldboard, a detachable share having a landside and a wing portion, and a frog beneath the moldboard and wing portion of the share and having a vertical and a wing portion, with a lug on the inner face of the landside of the share adapted to clamp against the free corners of the forward end of the vertical and wing portions of the frog respectively, means for holding the lug in clamped position comprising a threaded rod 110 connected at one end to the lug and at the other end to a support comprising a lever pivoted to the moldboard with its lower end adapted to come into securing relations with the share.

125 9. In a plow, the combination of a moldboard, a detachable share, and a frog for supporting the moldboard and share, with an element on the share for fastening the share to the frog, with a connection loosely 130

connected at one end to said element, a support on the plow for the opposite end of the connection comprising a fork through which the connection passes, a stop on the rear face 5 of the fork, a washer on the connection adapted to rest against the stop, and a tightening element on the connection behind the washer for drawing the share to place.

10. In a plow, the combination of a moldboard, a detachable plow share, and a frog for supporting the moldboard and share, with an element on the share for fastening the share to the frog, with a connection loosely attached at one end to said element, a 15 support on the plow for the opposite end of the connection comprising a fork through which the connection passes, a stop on the support to prevent lateral swinging of the connection, and a shiftable element for releasing the connection to permit the latter to 20 swing laterally free from the fork.

11. In a plow the combination of a moldboard, a detachable share having a landside and a wing portion and a lug thereon, and a 25 frog beneath the moldboard and wing portion of the share and having a vertical and

a wing portion, and an angled socket formed by the share and the lug thereon to receive and hold the forward end of the frog to secure the share laterally and vertically, and 30 means for drawing the share to seating position on the frog.

12. In a plow, the combination of a moldboard, a share having a landside and a wing portion, and a frog beneath the moldboard 35 and the wing portion of the share and having a vertical and a wing portion, with a lug on the landside of the share projecting rearwardly, inwardly and upwardly and adapted to wedge and clamp against the vertical and wing portions of the frog respectively and having surfaces to form, with the landside and wing of the share, a socket for the reception of the forward end of the frog, and means connected with the lug for drawing 40 the share and the lug to properly seated positions. 45
